UNITED STATES PATENT OFFICE.

HUNTER SMITH, OF BERKELEY, CALIFORNIA, ASSIGNOR OF TWO-THIRDS TO FRANK D. CHASE, OF BERKELEY, CALIFORNIA.

SUPERHEATER.

1,014,580.

Specification of Letters Patent. Patented Jan. 9, 1912.

Application filed April 15, 1911. Serial No. 621,359.

To all whom it may concern:

Be it known that I, HUNTER SMITH, a citizen of the United States, residing at Berkeley, in the county of Alameda and State of California, have invented certain new and useful Improvements in Super-heaters, of which the following is a specification.

This invention relates to steam super-heaters for boilers and has for its object to provide an improved apparatus of this kind which may be readily attached to any boiler, already in use.

The invention further has for its object to provide an improved steam super-heater for boilers so constructed and arranged that a large area of heating surface may be obtained within a limited space.

Referring to the accompanying drawings:—Figure 1 is an end view of a return tubular boiler and a super-heater constructed in accordance with this invention, partly broken away and in section with the boiler setting in cross section. Fig. 2 is a side view in elevation of the super-heater, partly in vertical section. Fig. 3 is a side view in elevation of the super-heater and the rear of a return tubular boiler with a portion of the boiler setting in longitudinal and vertical section. Fig. 4 is a plan view of the top of one side of the super-heater showing it as partly broken away and in horizontal section. Fig. 5 is a plan view in horizontal section of one of the columns of the super-heater. Fig. 6 is a detail view in vertical section of a portion of one of the columns of the super-heater.

In the accompanying drawings:—1 indicates the rear end of a boiler, and 2 indicates the boiler setting in cross section. The super-heater is constructed with pairs of columns 3 at each side thereof, each pair of columns having a double header 4 at the top and a double header 5 at the bottom. Each of the columns consists of a boiler tube 6 expanded at each end in the upper and lower heads in the usual manner of securing the ends of a boiler tube. The boiler tube 6 is inclosed by a casing composed of rings 7, preferably of cast metal, which rest on one another and serve to protect the thin boiler tube 6 from rapid destruction by fire, and also to increase the strength of the same. The rings 7 may be replaced from time to time and it will be noted that they are the

only parts of the column exposed to the direct action of the flames, the upper headers and the rest of the superstructure herein-after set forth being outside of the rear arch while the lower headers and connection are 60 below the pavement of the boiler setting.

Located within each boiler tube 6 is a vertical shaft 8 formed in sections 9, each of said sections having a section of a spiral flange 10, and connected together by means 65 of a square vertical projection 11 at the top of each section, which fits into the square socket 12 in the bottom of the section above the same. The edges of the spiral bear against the inner sides of the tube 6. The spiral shaft is detachably held in place by means of a spider 13 at each end which has a curved flange 14 which fits against the expanded end of the tube 6 and the rod 15 extends through the sections 9 and holds 70 the spiders 13 and the shaft in place by means of nuts 16 on the ends of the rod 15.

The headers are provided with hand holes closed by a plate 17 having a stem 17' and a spider 18 secured to the stem 17' by 80 means of a nut 19. A tight joint is formed between the plate 17 and the header by means of a bronze metal gasket 18'. Each of the double headers is provided with a lateral projecting flanged pipe 20, the top 85 headers 4 having the flanged pipes 20 connected to a pipe joint 21 which is formed with an elbow steam inlet pipe 22 and an elbow outlet pipe 23, said inlet pipes being 90 separated by partitions 24. The bottom headers 5 are connected together by a horizontal pipe 25 located beneath the pavement 95 of the boiler setting, the pipe 25 having its flanged ends connected to the flanged pipes 20 projecting from the bottom headers 5, and supported by brackets 27 on the bottom of the boiler setting.

28 is a connection on the pipe 25 for the attachment of a drip or steam trap.

One advantage of the construction of each 100 column lies in the fact that in adapting the super-heater to boilers of any kind the column may be made of any desired length by increasing or decreasing the number of sections thereof and the jointed connection of the sections 9 of the shaft preserve the alignment of the spiral flange.

The circulation through the super-heater is through the steam inlet 22, and the pipe 110 20 to the double-header. The flow now di-

vides and passes down through each tube 6 in the spiral path afforded by the flange 10. From the lower left hand double-header 5 steam passes horizontally through the pipe 25 to the right double header 5, and again divides and passes upward through the tubes 6 to the upper double header 4 and from thence through the pipe 20 and out of the outlet 23.

10 By means of the construction and arrangement of the double columns and double headers and the spiral path in each of the tubes 6, a large area of heating surface is provided within a narrow space.

5 15 What I claim is:—

1. In a steam super-heater for boilers, a column consisting of a boiler tube, a header at each end of the tube, a casing built up of metal rings inclosing said tube, a shaft 20 in said tube extending from end to end thereof, and a spiral flange extending from end to end of said shaft, said shaft and spiral flange being formed in sections.

2. In a steam super-heater for boilers, a column consisting of a boiler tube, a header secured to each end of said tube, a casing inclosing said tube and formed of a column of

detachable metal rings and located between said headers, a shaft having a spiral flange extending from end to end of said tube and formed of detachable sections, a rod extending through said shaft, and a spider on each end of said rod detachably secured thereto, and bearing against the end of the tube.

30

35

3. A steam super-heater for boilers, consisting of a pair of columns at each side thereof, each of said pairs of columns having a double header at the top and bottom, and each of said columns consisting of a 40 boiler tube, a casing inclosing said tube and formed of built up metal rings, and a shaft in said boiler tube having a spiral flange, the lower double headers being connected by a pipe and one of the upper double headers 45 being provided with an inlet pipe and the other with an outlet pipe.

In testimony whereof I affix my signature in presence of two witnesses.

HUNTER SMITH.
